UNITED STATES PATENT OFFICE

WILLIAM A. ROHMAN, OF ATTLEBORO, MASSACHUSETTS, ASSIGNOR TO D. E. MAKE-
PEACE COMPANY, OF ATTLEBORO, MASSACHUSETTS, A CORPORATION OF MASSA-
CHUSETTS

DESIGN FOR A WIRE OR SIMILAR ARTICLE

Application filed February 20, 1931. Serial No. 38,742. Term of patent 3½ years.

To all whom it may concern:

Be it known that WILLIAM A. ROHMAN, a citizen of the United States, residing at Attleboro, in the county of Attleboro, and State of Massachusetts, has invented a new, original, and ornamental Design for Wire or Similar Article, of which the following is a specification, reference being had to the accompanying drawings, forming a part thereof.

Fig. 1 is a plan view of a piece of wire or similar article embodying my new design.

Fig. 2 is a side elevation thereof.

I claim:

The ornamental design for wire or similar article substantially as shown.

In testimony whereof I affix my signature.

WILLIAM A. ROHMAN.
